UNITED STATES PATENT OFFICE.

SINCLAIR W. CHILES, OF SOUTH BETHLEHEM, PENNSYLVANIA.

DIRT-ELEVATING PUMP.

No. 834,606.

Specification of Letters Patent.

Patented Oct. 30, 1906.

Application filed June 29, 1906. Serial No. 324,050.

To all whom it may concern:

Be it known that I, SINCLAIR W. CHILES, of South Bethlehem, county of Northampton, and State of Pennsylvania, have invented an Improvement in Dirt-Elevating Pumps of which the following is a specification.

My invention has reference to dirt-elevating pumps; and it consists of certain improvements which are fully set forth in the following specification and shown in the accompanying drawings, which form a part thereof.

The object of my invention is to provide an efficient apparatus which may speedily and inexpensively elevate dirt or other material from cassions, wells, and other deep places from which such material is to be excavated or moved.

My invention employs compressed air, steam, or liquid under high pressure as the motive force for moving the dirt through the pipes, and my improvements are now more practically directed to the means by which the dirt may be fed to the pipe intermediate of the applications of the compressed air, whereby the latter may be brought into play upon each fresh charge of material to put it into circulation in its passage upward.

My invention consists of a case having a charging-hopper or entrance, a discharge-outlet for the discharge of the material, and an inlet for the compressed air, combined with a movable hollow valve portion inclosed within the case and having apertures corresponding to the apertures in the case, but so disposed that when the hopper is open to the interior the air-inlet and discharge openings are closed, and vice versa, so that the interior may be first charged and subjected to high pressure to discharge the contents.

My invention also comprehends means within the hollow valve portion for breaking down or disintegrating any material which might pack and clog the machine, said means being operative during the time of discharging the material from the apparatus.

My invention also embodies many details of construction, which, together with the features above specified, will be better understood by reference to the drawings, in which—

Figure 1 is a transverse sectional elevation of my improved dirt-elevating pump. Fig. 2 is a longitudinal sectional elevation of the same. Fig. 3 is an elevation of the same with a portion of the hopper broken away,

and Fig. 4 is a cross-section through one of the bearings of the case and valve part.

A is the case, and is shown in spherical form, though this is not at all essential. The case is provided with an opening D at the top, 60 which is fitted with a conical hopper B, through which the dirt is thrown into the case. This hopper may be provided with a coarse grating or screen B' to prevent large stones entering the case. The case is also 65 provided at one side near its bottom with an air-inlet F and on the opposite side about its middle with a discharge-opening E, preferably directed obliquely upward.

The case A is formed of two parts—namely, 70 A' and A²—which are fitted together by a tongue-and-groove joint, as shown at C, which while maintaining a comparatively tight joint allows for adjustment to compensate for wear between the movable valve 75 portion J and the case. As shown, the union of the two parts A' A² is in a plane passing through the axis of the pump and slightly inclined, so as to include the discharge-opening E in the upper section A'. The two parts A' 80 A² are flanged, and bolts c, passing through the flanges, clamp the two parts together. Set-screws G, Fig. 3, are employed to adjust the two parts and limit the extent to which they are drawn together. As the pressure is to force the parts A' A² apart, it is evident that four of these set-screws G are sufficient, whereas many bolts c are necessary to resist the internal pressure when moving the materials.

J is the movable valve portion and is shown as a hollow sphere having the apertures D', E', and F', corresponding to the apertures D, E, and F in the case, but with the difference that when the apertures E' F' are in alignment with the apertures E F to form a through passage-way the aperture D' is out of alignment with the aperture D, and vice versa. To reduce the friction and insure practically tight joints, I prefer to provide 95 the inner part of the case adjacent to the apertures D, E, and F, respectively, with wear-faces d, e, and f, against which the valve part J directly works.

I prefer to thicken the interior portion of 105 the valve J between the apertures E' and F', as at R, so as to more properly guide the dirt through the discharge-opening E by the blast of air from the inlet F. This valve J is adapted to oscillate in bearings I, in which the 110

trunnions J' are journaled. These bearings are split and the two halves adjusted toward each other by set-screws i . These bearings I are carried in side extensions H of the case 5 A , and they, like the parts $A' A^2$, are provided with joints C of tongue-and-grooved character, as shown in Fig. 4. The trunnion J' on one side of the valve extends outward, as at J^2 . Journaled in the trunnions is a 10 transverse shaft K , having within the valve J a series of arms L , adapted to break or disintegrate any dirt or packed material which may be in the valve, so as to insure its passage through the discharge-opening E . The 15 end of this shaft K extends beyond the trunnion part J^2 and is fitted with a ratchet-wheel N . Journaled upon the shaft K between the ratchet-wheel and trunnion is a lever M , which carries a pawl n , engaging with the 20 ratchet-wheel, and also a latch O , which may be made to engage with a notch in the part J^2 of the trunnion for rocking the valve portion J by the lever M . If there is any clogging of the interior, the latch O is raised and 25 the lever M rocked for rotating shaft K and its arms L .

The operation of the apparatus will now be understood. The valve J is turned so as to bring the opening D' in line with the hopper-opening D and close the openings E and F . The dirt is then shoveled into the hopper B and passes into the valve-body J . The valve is then turned a quarter of a revolution to the position shown in Fig. 2, and this permits the air under about sixty pounds per 30 square inch to rush through the opening F and drive the dirt upward through the outlet E and the piping connected therewith. Any dirt which may pass between the valve 35 part J and the casing A will act as a packing to prevent escape of air through the joint C . The air may be supplemented with water, if so desired, so as to keep the dirt more in a 40 pasty or fluid condition. After the discharge of the contents of the valve portion J it is rocked back to the original position and again recharged, the air-pressure being shut off at this time and the contents on the discharge side of the opening E being prevented 45 from descending backward into the valve. The action is intermittent, and the materials 50 are propelled through the discharge-pipe in an interrupted advance.

It is evident that the spherical form of my 55 apparatus is strong and condensed; but it is not at all essential, as any other shape may be employed so long as the valve may rotate or rock within its case and control the several ports. Therefore, while I prefer the construction shown as being excellently adapted for 60 the purposes of my invention I do not restrict myself to the details, as these may be modified or varied without departing from the spirit of the invention.

Having now described my invention, what 65 I claim as new, and desire to secure by Letters Patent, is—

1. In a pump for lifting dirt or other material, a case having a hopper-port, an air-inlet port and a discharge-port, combined with 70 a hollow valve pivoted within the case and having apertures corresponding to the ports in the case but so arranged that when its aperture is open to the hopper-port the other apertures are closed to the inlet and discharge 75 ports and vice versa, and means for imparting to the valve a rotary motion.

2. In a pump for lifting dirt or other material, a case having a hopper-port, an air-inlet port and a discharge-port, combined with 80 a hollow valve pivoted within the case and having apertures corresponding to the ports in the case but so arranged that when its aperture is open to the hopper-port the other apertures are closed to the inlet and discharge 85 ports and vice versa, means within the valve part for breaking or disintegrating the dirt therein, and means for imparting to the valve a rotary motion.

3. In a pump for lifting dirt or other material, a case having a hopper-port, an air-inlet port and a discharge-port, combined with 90 a hollow valve pivoted within the case and having apertures corresponding to the ports in the case but so arranged that when its aperture is open to the hopper-port the apertures are closed to the inlet and discharge 95 ports and vice versa, a rotating shaft having arms within the valve part for disintegrating the dirt, a ratchet-wheel on the end of the 100 shaft and means for imparting to the valve and to the ratchet-wheel a rotary motion.

4. In a pump for lifting dirt or other material, a spherical case having a hopper-port at the top and an air-inlet port and discharge-port lower down, combined with a hollow 105 spherical valve fitted within the case and having apertures for the several ports in the case but so arranged that when the hopper-port is open the inlet and discharge ports are 110 closed and vice versa.

5. In a pump for lifting dirt or other material, a spherical case having a hopper-port at the top and an air-inlet port and discharge-port lower down and formed of two parts A' 115 A^2 connected by a tongue-and-grooved joint C , combined with a hollow spherical valve fitted within the case and having apertures for the several ports in the case but so arranged that when the hopper-port is open the 120 inlet and discharge ports are closed and vice versa and also having trunnions journaled in the case on a line with the division between the parts $A' A^2$ thereof, and means operating upon one of the trunnions for moving the 125 valve portion.

6. In a pump for lifting dirt or other material, the combination of the case having hop-

per-opening D, air-inlet F and discharge-outlet E, with a hollow valve portion J having the apertures D' F' and E' arranged as described and also having the interior filled in 5 as at R to form a direct guide-floor between the apertures F' and E'.

7. In a pump for lifting dirt or other material, the combination of the case having hopper-opening D, air-inlet F and discharge-outlet E, with a hollow valve portion J having the apertures D' F' and E' arranged as described, means for imparting a rocking motion to the valve portion, and a rotary shaft 10 extending through the valve portion and having arms for breaking down the dirt.

8. In a pump for lifting dirt or other material, the combination of a case having a hopper an inlet for compressed air and a dis-

charge-outlet, with a valve device within the case to open the hopper and close the air- 20 inlet and discharge-outlet and vice versa.

9. In a pump for lifting dirt or other material, the combination of a case having a hopper an inlet for compressed air and a discharge-outlet, with a valve device within the 25 case to open the hopper and close the air-inlet and discharge-outlet and vice versa and means within the valve device for breaking down the dirt.

In testimony of which invention I hereunto 30 set my hand.

SINCLAIR W. CHILES.
